APPARATUS AND METHOD FOR EXCLUDING AIR BUBBLES FROM SUBMERGED WELL PUMP

Dean H. Aulman, Woodland, Calif., assignor of one-half to Harry E. Aulman, Woodland, Calif.

Application June 6, 1956, Serial No. 589,704

9 Claims. (Cl. 103—203)

This invention comprises novel and useful improvements in an apparatus and method for excluding air bubbles from submerged well pumps and is especially designed to overcome the detrimental effect of a falling water level upon the efficiency of operation of submerged well pumps.

In certain regions having seasonal or for other reasons receding water levels, and especially in those regions having many irrigation wells, it has been found that the efficiency of submerged water pumps therein is detrimentally affected by a recession in the water levels. Particularly, in irrigation and other wells in which the well casings have perforations above the pumping level of the well, seasonal or other recessions of the water level below the apertures or passages by which the water bearing strata produces a flow into the well casing, result in the dropping and splashing of the incoming water, often from considerable heights, from the water admitting perforations or openings to the water level within the well casing. This falling water entraps and carries with it thousands of air bubbles which by the force of the falling water are forced below the pumping water level and adjacent to the intake of the submerged pump. As is well known, the admission of air to the intake of a submerged pump has a detrimental effect upon the efficiency of the pump, thereby lessening the flow of water delivered thereby and also increasing the expense of the user.

It is therefore the primary purpose of this invention to provide an apparatus and a method whereby the above mentioned detrimental effects of a receding water level in wells upon the efficiency of a submerged water pump therein may be avoided.

An important object of the invention is to provide an apparatus which shall be of a simple and yet a dependable construction and operation for overcoming and preventing the delivery of air bubbles to the intake of the pump by water flowing into the well.

A further object of the invention is to provide an apparatus and method in accordance with the foregoing objects which shall be always ready for use and may be selectively rendered operative or inoperative as desired.

A further object of the invention is to provide an apparatus and method whereby the inflowing water of a well may be selectively prevented from carrying air bubbles below the water level during the inflow of the incoming water, and which apparatus and method may be controlled in a simple manner from the surface.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a view in vertical central section through a portion of a well casing and illustrating the manner in which the principles of this invention are applied to a submerged pump therein;

Figure 2 is an enlarged detail view in vertical section

2

taken substantially upon the plane indicated by the section line 2—2 of Figure 1 and showing in full lines the protective device of this invention in its inoperative position, and indicating in dotted lines the position of the protective device during its use;

Figure 3 is a horizontal sectional view taken substantially upon the plane indicated by the section line 3—3 of Figure 2 and showing the manner in which the protective device is secured to the flow line or pump tubing of the well;

Figure 4 is a horizontal sectional view taken substantially upon the plane indicated by the section line 4—4 of Figure 2; and

Figure 5 is an assembly perspective view of the various elements forming the protective device of this invention.

Referring first to Figure 1 which illustrates by way of example one manner of applying the principles of this invention, it will be seen that there is disclosed a well casing 10 extending through an upper water producing strata 12 and downwardly into a lower water producing strata 14. At the surface, the casing is provided with a casing head 16 from which a water delivery pipe 18 extends, the water delivery pipe being connected to a flow or pump tubing 20 disposed in the casing and extending towards the bottom of the well, and carrying at its lower end a conventional submerged type of well pump 22.

It should be understood that the submerged pump 22 may be of any desired character and may be operated in any desired manner, and since the principles of this invention are not limited to any particular mode of operation or construction of pump, a further description of the same is deemed to be unnecessary.

As will be seen from Figure 1, the lower portion of the well casing 10 which extends through the lower water producing strata 14 is perforated as at 24 to freely admit the passage of the water into the casing, while those portions of the casing which extend through other water producing strata, such as the strata 12, are usually likewise perforated, as at 26. Indicated by the numeral 28 is the normal water level of the soil above the water producing strata 12. When the water level within the well casing stands substantially at or above the apertures 26 of the topmost water producing strata, the water therefrom flows into the well casing without any appreciable splash and produces no problem. However, when the water level within the casing drops below the water level of the topmost water producing strata, such as the strata 12, to any appreciable extent, such as to the level indicated by the line 30, so that this pumping level in the casing is spaced closely above the submerged pump, an important problem exists. As the water from the producing strata 12 passes through the apertures 26 and falls downwardly in the casing to the water level 30 therein, the stream of falling water splashing upon this water level carries with it air bubbles which may be driven below the level 30 to a sufficient distance to be drawn into the intake of the submerged pump 22. When this occurs, the introduction of the air bubbles to the pump intake very seriously curtails and detrimentally affects the efficiency of the pump, reducing its capacity and increasing the expense of obtaining water for the user.

In accordance with this invention, a method has been devised and a safety device and attachment has been provided whereby the above mentioned objections may be satisfactorily overcome.

As will be seen especially from Figures 2 and 5, the apparatus provided for this purpose, indicated generally by the numeral 32, consists of a sleeve 34 which is slidably received snugly upon the pump tubing 20. Adjacent its upper end, this sleeve is provided with an annular, projecting collar or shoulder 36 having therein an axially extending radial notch 38 for a purpose to be subsequently

set forth. Above this sleeve, the upper extremity of the sleeve is provided with screw threads for receiving fastening bolts 40.

At its lower end, the sleeve 34 is externally threaded, as at 42, for the reception of a nut 44. Frictionally embracing the sleeve 34 and retained thereon between the annular ring 36 and the securing nut 44 is a hollow sleeve 46 of rubber or other fluid impervious material. A flexible conduit 48 extends through a reinforcing patch 50 formed on preferably the upper portion of the inflatable sleeve 46, this flexible conduit conveniently extending through the notch 38, and being detachably coupled, as by a coupling member 52, to a copper or other tubing 54, which extends into the casing head 16 above the surface of the ground. Above the surface of the ground, the copper tubing 54 is connected through any suitable control valve, not shown, to any other suitable source of air pressure, such as an air compressor or the like.

The application of this device to a submerged well pump is as follows: The inflatable sleeve 46 being secured to the member 34 by the ring 36 and nut 44 and having its flexible conduit 48 coupled to the fluid pressure line 54, is applied to a section of the pump tubing 20, and is secured thereto by the bolts 40 which abut against the exterior surface of the pump tubing, at any convenient distance above the submerged water pump 22.

In its collapsed position shown in Figure 2 in full lines, the inflatable sleeve 46 offers no obstruction of the cross-sectional area of the well casing whereby incoming water from the water producing strata may freely enter the well casing and descend to the pumping water level standing therein. However, when the water within the casing has receded either by pump or for other reasons to an extent as that indicated by the water pumping level 30, whereby the incoming water from the producing water bearing strata or strata above tends to splash or fall upon the pumping level in the casing and thus produce and entrain air bubbles therewith detrimentally affecting the operation of the submerged water pump by reducing pump efficiency, the sleeve 46, being positioned at an appropriate distance for this purpose, is inflated to or beyond the dotted line position indicated at 60 in Figure 2, by the admission of air or other fluid under pressure from the conduit 54 and flexible tubing 48 into the sleeve 46. When properly inflated or expanded, the sleeve will reduce and obstruct the cross-sectional area of the well casing to such an extent that a higher head of water will be built up and maintained above the apparatus and inflated sleeve, as long as water is falling from the level of apertures 26, than when the sleeve is deflated or is not sufficiently inflated. The incoming falling water will strike upon this built up water level above the sleeve. But the down draft of water, by virtue of the restriction or throttling effect by the sleeve, will be slowed up sufficiently to enable air bubbles to ascend faster than the downflowing stream drops, thereby preventing the intake of air to the pump. By this sleeve, the water will then be sufficiently slowed up as to its down draft to the pump suction intake to permit any entrained air bubbles to materially rise through the water and escape and thereby will be prevented from forcibly driving air bubbles below the water level and to the vicinity of the intake of the submerged pump. For this purpose the obstruction interposed to the down draft of the water and entrained air bubbles must be such as to reduce the speed of this down draft to less than the speed at which entrained air bubbles will rise in the water. It will probably be necessary to adjust the vertical position of the sleeve and its expanded area individually for each well bore. The sleeve should be inflated no more than necessary for the above purpose, in order that the flow of water shall be restricted no more than sufficient to permit escape of the entrained air bubbles. When no more air bubbles are visible at the pump discharge, it will be evident that the sleeve is sufficiently inflated.

As will be perceived, the expandible sleeve may be readily inflated or deflated from the surface of the ground, as desired. Thus, when the water level stands sufficiently high in the well to produce no problem from bubbles carried by the inflowing water, as during rainy seasons or periods when the standing water level within the well is high, the casing may be deflated. However, when for any reason the water level drops to a height which would be detrimental in the manner above described, the protective sleeve can be readily inflated from the surface as long as its services may be required.

An important feature of this invention is that the protective device may be readily applied to existing wells and pump lines; and especially may be applied to irrigation wells with which this problem is extremely prevalent. The device is readily adjusted to the conditions produced by different water levels and possesses relatively few parts and is of a durable nature.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A protective device for submerged pumps in well casings comprising an inflatable member, means for supporting said member in a well casing at a position between the pumping water level in the casing and a higher level at which water enters the casing from a water producing strata, means for inflating the member to a size at which it intercepts the incoming water from the higher level and slows its speed of down flow from the higher water level to the intake of a submerged pump to a speed just less than that at which entrained air bubbles will naturally rise out of the water, thereby eliminating the entrainment for air bubbles to the inlet of the submerged pump.

2. The combination of claim 1 wherein said supporting means engages the pump tubing of the submerged pump for supporting the inflatable member therefrom.

3. The combination of claim 1 wherein said supporting means engages the pump tubing of the submerged pump for supporting the inflatable member therefrom, said inflatable member surrounding said pump tubing.

4. The combination of claim 1 wherein said supporting means engages the pump tubing of the submerged pump for supporting the inflatable member therefrom, said mounting means being slidable and vertically adjustable upon the pump tubing.

5. The combination of claim 1 wherein said inflating means comprises a tube in said casing extending from a controlled source of fluid pressure above the surface and communicating with said member.

6. The combination of claim 1 wherein said supporting means includes a sleeve slidably received upon the pump tubing of said submerged pump, said inflatable member surrounding said sleeve, fastening means securing said sleeve to said pump tubing.

7. The combination of claim 1 wherein said supporting means includes a sleeve slidably received upon the pump tubing of said submerged pump, said inflatable member surrounding said sleeve, fastening means securing said sleeve to said pump tubing, a ring on the upper end of the sleeve, for limiting upward movement of the member thereon.

8. The combination of claim 1 wherein said supporting means includes a sleeve slidably received upon the pump tubing of said submerged pump, said inflatable member surrounding said sleeve, fastening means securing said sleeve to said pump tubing, a ring on the upper end of the sleeve, for limiting upward movement of the mem-

ber thereon, a retainer on the lower end of the sleeve limiting downward movement of the sleeve.

9. The combination of claim 1 wherein said supporting means includes a sleeve slidably received upon the pump tubing of said submerged pump, said inflatable member surrounding said sleeve, fastening means securing said sleeve to said pump tubing, a ring on the upper end of the sleeve, for limiting upward movement of the member thereon, said ring having a notch, said inflating means passing through said notch.
